UNITED STATES PATENT OFFICE

2,149,237

SEWING MACHINE

Charles Edward Barrett, Yonkers, N. Y., assignor
to Alexander Smith & Sons Carpet Company,
Yonkers, N. Y., a corporation of New York

Application October 9, 1937, Serial No. 168,163

2 Claims. (Cl. 112—256)

It is sometimes desirable in the stitching of 5
bindings to the edges of fabrics, to use a binding,
one side of which, including the part through
which the needle passes, is coated with dry cement
which becomes adhesive when heated. This
is a thickened latex, which is not entirely dry, but
is a gummy substance, and some is picked up by
the needle and needle thread and carried to the
loop taker which becomes coated and interferes
10 with the ready passage of the loop of needle
thread thereover.

The object of this invention is to provide a solvent
for this cement and a wiper which will apply
the solvent and remove the softened and dissolved
cement from the loop taker.

In the accompanying sheet of drawings which
forms a part of this description,

Figure 1 is a vertical section through the bed
plate of a sewing machine on the line I—I of Fig.
2, transverse to the direction of feed, showing the
loop taker, means for actuating the same and the
wiper which embodies this invention.

Fig. 2 is a vertical section of the same on the
line II—II of Fig. 1, at right angles to the plane
25 of Fig. 1.

The invention is shown in connection with the
sewing machine which is set forth in United
States Patent No. 1,975,728, dated October 2, 1934,
for a sewing machine for attaching a binding
30 strip to the cut edge of a rug or carpet and No.
545,882, dated September 10, 1895, wherein the
loop taker is an oscillating shuttle, but the in-
vention is not restricted in its broader aspects
to a sewing machine with this type of loop taker
35 or for this particular use.

The sewing machine has the usual overhanging
bracket arm, not shown, and bed plate 10. An
eye-pointed needle 11 is laterally vibrated and
vertically reciprocated alternately along the lines
40 a—a and b—b to form a zigzag overedge lock-
stitch seam in cooperation with a loop taker 12.
The loop taker is an oscillating shuttle with a
beak 13 which engages the needle thread, forms a
loop thereof and passes the shuttle therethrough.
45 The shuttle has an axial pin 14 which is journaled
in the bobbin case 15 containing the lower thread
supply and provided with an arm 16 which enters

a holding notch in the ring 17 which is fastened
to brackets 18 depending from the bed plate. The
ring loosely holds the bobbin case. A shuttle-
actuating rock-shaft 20 has fixed upon its for-
ward end a hub 21 of a shuttle driver 22 which
alternately engages the two ends of the shuttle in
producing the to and fro oscillating movement
of the shuttle. The rock-shaft has fixed upon its
rearward end a crank arm 23 having a stud 24
embraced by a laterally extending forked arm 25
10 of a rock-shaft 26 which is provided with a second
lateral arm 27 carrying a stud 28 and engaged by
one end of a link connection 29 which is suitably
reciprocated in unison with the main shaft of the
machine as shown in the above named patents. 15
The shuttle turns with its axial pin and is loosely
held between the ring in front and a wiper 30 in
the rear which is carried by a fixed part of the
machine.

It has been found that in the operation of the 20
machine some of the gummy latex, with which
the binding to be stitched has been coated, tends
to accumulate particularly on the rear face of
the shuttle and prevents the loop of the needle
thread from freely passing thereover. To stop
25 this accumulation the wiper is of soft material
with capillary pores, as felt, and is kept saturated
with a suitable solvent for the latex, as oil, and
the wiper contacts with the oscillating shuttle,
discharges the solvent and wipes off the softened
30 and dissolved latex. There is only a loose contact
between the shuttle and the wiper so that there
will be no interference with the passage between
them of the needle thread.

I claim:

1. In a sewing machine, a loop taker, means for actuating the loop taker, and a wiper carried by a fixed part of the machine and engaging a substantial area of one side of the loop taker over which the loop contacts.
2. In a sewing machine, a loop taker, means for actuating the loop taker, and a wiper of porous material carried by a fixed part of the machine and engaging a substantial area of one side of the loop taker over which the loop contacts.
